UNITED STATES PATENT OFFICE.

PAUL ZÜST, OF RHEINECK, AND JOHANN METZGER, OF HEIDEN, SWITZERLAND,
ASSIGNORS TO THE FIRM OF STAHELI, RIETMANN & CO., OF ST. GALLEN,
SWITZERLAND.

PANTOGRAPH EMBROIDERY-MACHINE.

1,341,160.

Specification of Letters Patent.

Patented May 25, 1920.

Application filed July 13, 1916, Serial No. 109,136. Renewed January 23, 1920. Serial No. 353,592.

To all whom it may concern:

Be it known that we, PAUL ZÜST and JOHANN METZGER, both citizens of the Republic of Switzerland, the first residing at 5 Rheineck, Switzerland, the second residing at Heiden, Switzerland, have invented certain new and useful Improvements in Pantograph Embroidery-Machines, of which the following is a specification.

10 The object of our invention is a device for shuttle embroidery machines for the manufacturing of curtains. The invention lies in the fact that for every single shuttle, two or more needles come into action simultaneously and serve to form a kind of festoon or decorative chain embroidery; also in the fact that the embroidery frame is moved by means of a pantograph in the transmission ratio of 1:1.

15 20 The object of the invention is shown by means of an example on the drawing, in the following way:

Figure 1 shows a longitudinal section of the stitch, on a considerably enlarged scale.

25 Fig. 2 is a side view of the arrangement of the needles and of the shuttle track.

Fig. 3 is a front view of the arrangement of the needles.

30 Fig. 4 is a plan view of the arrangement of the needles.

Fig. 5 is a front view of the shuttle track.

Fig. 6 shows the pantograph in connection with the embroidery frame.

In Fig. 1, the numbers 1 and 2 indicate the 35 foundation material (tulle and application material), which has to be embroidered. 3 and 4 represent two adjacent needle threads which lie directly alongside one another on the front side of the embroidery. The shuttle thread is indicated by 5. The slip-knots 40 *a* and *b*, which are formed by the needle threads and lie alongside one another, are, according to the present invention, simultaneously produced, and tied up in pairs by

45 a shuttle. For this purpose, for every shuttle *s*, two needles 6 and 7, lying alongside one another, are attached to the needle bar, which latter is indicated on the drawing by 9. One of the needles lies somewhat higher than the 50 other, this difference of height being attained by means of the small block 8, which contains a hole for the upper needle 7, and a groove for the lower needle 6, which groove lies exactly above a groove situated in the

needle bar 9. The needle 6, together with the small block 8, is fastened to the needle bar 9 by means of the screw 10, while the needle 7 is tightly fixed into the hole of the small block 8 by means of the separate screw 11. The eyes of both needles thus lie in such a manner that the needles can be threaded from the same side. Owing to the arrangement of two needles for every shuttle, the middle hole 13 of the shuttle track 12 has been accordingly made of larger dimensions 65 than is otherwise customary. Fig. 5 shows how the needles lie opposite to one another in the shuttle track.

In order, when embroidering, to be able to use the embroidery card exactly according 70 to design and enlargement of the pattern, the machine is also provided with a pantograph 14, which has a ratio of transmission of 1:1, instead of 1:6, as is customary. The pantograph is connected with the 75 embroidery frame, and can be adjusted. The transmission of the pantograph naturally requires a greater expenditure of effort on the part of the embroiderer, but this may be partially overcome by the spring 18 which 80 grips the lower arm of the pantograph. Moreover, the pantograph is balanced in a sidewise direction by two springs 16 and 17 working against one another, as soon as it is moved from its middle position to one or 85 other side. These two springs are attached to the upper part of the pantograph.

In connection with the embroidery frame 15, it should be remarked that same must be fitted into the machine frame in such a manner that it can be moved in a sidewise direction for the execution of large patterns in connection with the pantograph. 90

The result of the invention is that two 95 stitches lying alongside one another can be embroidered at the same time. This consequently quickly produces a double-row stitch, which does not become undone when the embroidery is being cut off or washed.

We claim:

1. An embroidering machine having a pantograph operated fabric frame and a horizontal needle bar extending along said frame; in combination with needles arranged in pairs along said bar and a single shuttle simultaneously coöperating with each pair of needles.
2. An embroidering machine having a

100

105

pantograph operated fabric frame and a horizontal needle bar extending in front of said frame; in combination with needles mounted in pairs along said bar, the needles of each pair being both vertically and horizontally spaced, and a single shuttle simultaneously coöoperating with each pair of needles.

3! An embroidering machine having a
10 pantograph operated fabric frame and a horizontal needle bar; in combination with a block at each stitching position on said bar, a screw for clamping said block to said bar

and thereby clamping a needle between the block and bar, said block having a horizontal needle seat vertically and laterally spaced from the first needle position, and a screw for clamping a needle in said seat. 15

In testimony whereof we have affixed our signatures in presence of two witnesses.

PAUL ZÜST.

JOHANN METZGER.
